UNITED STATES PATENT OFFICE.

GEORGE E. MITTINGER, JR., OF NEW CASTLE, PENNSYLVANIA.

DESIGN FOR A DISH-PAN.

44,932.

Specification for Design.

Patented Nov. 25, 1913.

Application filed October 14, 1909. Serial No. 522,688. Term of patent 14 years.

To all whom it may concern:

Be it known that I, GEORGE E. MITTINGER, Jr., a citizen of the United States, residing at New Castle, in the county of Lawrence and State of Pennsylvania, have invented a new, original, and ornamental Design for Dish-Pans, of which the following is a specification, reference being had to the accompanying drawing, forming part thereof.

The figure is a bottom perspective view of my dish-pan showing my design.

I claim:

The ornamental design for a dish pan, as shown.

GEORGE E. MITTINGER, JR.
Witnesses:

EDWARD J. O'BRIEN,
Miss M. CAMPBELL.
